UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

SPOTLIGHT.

Application filed October 24, 1921. Serial No. 509,885.

To all whom it may concern:

Be it known that I, ARTHUR L. STAPLES, a citizen of the United States, residing at New Haven, in the county of New Haven, 5 State of Connecticut, have invented certain new and useful Improvements in Spotlights; and I do hereby declare the following to be a full, clear, and exact description of the invention, such as will enable 10 others skilled in the art to which it appertains to make and use the same.

The present invention relates to battery hand lamps of the type wherein the character of the beam of light can be altered by 15 varying the relative position of the lamp and reflector.

It is an object of the present invention to provide a hand lamp in which the battery and reflector have substantially fixed 20 positions in the casing and in which the desired change in the character of the beam of light delivered by the hand lamp is effected by shifting the lamp bulb with respect to the battery and reflector.

25 It is a further object of the invention to protect the inner and fragile terminal of the lamp from the forward thrust and from destructive impact of the upper battery terminal, to provide for ready renewal of the 30 lamp, to provide for easy access to various parts of the hand lamp mechanism, to insure against short-circuiting of the battery and inadvertent lighting of the lamp, and to secure other advantages as herein- 35 after pointed out more at length.

In the accompanying drawings:—

Figure 1 is a sectional elevation of one embodiment of the invention;

Fig. 2 is a fragmentary section of the 40 same embodiment;

Fig. 3 is a section on the line 3—3 of Fig. 1;

Fig. 4 is a section on the line 4—4 of Fig. 1;

45 Fig. 5 is a fragmentary section of the front end of the casing showing slots for the adjusting cross-bar;

Figs. 6, 7 and 8 are details of the lamp-supporting mechanism.

50 In the embodiment illustrated, the hand lamp comprises a casing 1 of insulating material such as fiber, in which are a plurality of dry cells 2 placed end to end in a pasteboard carton in conformity with usual practice. The naked bottom of the

lowermost dry cell rests on and makes electrical connection with a coiled spring 3 carried by a metal bottom cap 4 threaded to a collar 5 on casing 1. A metal strip 6 connects collar 5 with a switch housing 7 in conformity with usual practice. At the opposite or front end of casing 1 is a flaring metal head 8 fastened to the fiber casing by rivets 9 and having its front portion threaded to receive a lens-supporting ring 10. A reflector 11, substantially parabolic in outline, has its outer flange gripped between collar 10 and the front edge of head 8 so that the reflector is clamped in fixed relation to the casing.

70 Coiled spring 3 holds the battery of dry cells with yielding pressure against an abutment consisting of a metal shell or bridge 12 (Fig. 3). The ends or outer edges of the metal shell are turned up, as 75 shown in Fig. 8, to form ears through which are passed rivets 13 to hold the bridge in rigid relation to casing 1. A washer 14 of insulating material is preferably used to hold the upper zinc edge of the battery out 80 of electrical contact with bridge 12. At the center of this bridge or abutment and preferably integral therewith is a cylinder 15 which serves as a guide for a movable lamp support. The lamp support comprises a 85 plunger 16 of insulating material, cylindrical in form and movable up and down in cylinder 15. The hollow upper end of this lamp support is threaded to act as a socket for an incandescent lamp. This lamp can 90 advantageously be of the type wherein the light-giving filament is concentrated within a small area. Plunger 16 has a central hole in which is housed a coiled spring 17, the upper end of which makes connection with

95 and is held in place by an eyelet 18 and the lower end of which makes yielding contact with the upper terminal 19 of the dry battery. A metal collar 20 is slipped over the upper reduced end of plunger 16 and 100 has an integral finger 21 (Figs. 4 and 6) struck up therefrom which passes through a slot 22 and makes electrical connection with the threaded terminal of the lamp. Integral with this collar is a lug 23, the outer edge of which makes electrical connection with the front yielding end of a stationary contact strip 24. Strip 24 is held in place by a rivet 25 and its lower end is bent to 105 form a finger 26 which protrudes through a 110

slot in the fiber casing and forms one of the contacts of the switch mechanism by which the flow of battery current to the lamp bulb is controlled. The other switch element is a flexible leaf spring 27 fastened to housing 7 by a rivet 28 and having a thumb pan or push button 29 by which it can be manipulated. Other forms of switch mechanism can be used in place of that shown in the drawing.

With the arrangement above described, the battery circuit is from battery terminal 19 through spring 17 and eyelet 18 to the inner terminal of the lamp, then through 15 the lamp to finger 21 (Fig. 4), and then through collar 20, lug 23, strip 24, finger 26, spring 27, housing 7, conductor 6, collar 5, cap 4, and spring 3 to the other terminal of the battery.

20 To provide for changes in the character of the beam of light projected by the incandescent lamp through the lens or glass 30 at the front end of the casing, there is provided a sleeve 31 threaded to the lower 25 portion of head 8 and having an annular groove in which is received the ends of a cross-bar 32. This cross-bar 32 fits in a groove 33 (Fig. 7) of plunger 16 so that on rotation of the adjusting sleeve 31 the bar 30 will move longitudinally of the casing in slots 34 and 35 and thus will raise or lower plunger 16 and the lamp carried thereby. Spring 17 will expand or contract as occasion may require to maintain electrical connection between the stationary battery terminal 19 and the inner terminal of the lamp bulb. Similarly, lug 23 by sliding along the yielding end of strip 24 will maintain electrical connection to the outer terminal of the 40 lamp. Upward movement of cross-bar 32 is limited by its engagement with the lower edge of head 8 and downward movement is limited by engagement of the bar with the bottom ends of slots 34 and 35.

45 The opening in reflector 11 is large enough to permit free sliding movement therethrough of plunger 16 so that by simply turning the adjusting sleeve 31 the operator can shift the lamp with respect to the reflector and thus change the character of the beam of light delivered by the hand lamp. With a hand lamp as thus constructed, the rays of light may be focused on a distant object or may be spread over a relatively 55 wide area, as desired. Throughout the manipulation, the battery remains stationary in the casing and is firmly held against its abutment by coiled spring 3.

In the embodiment shown in the drawings, 60 the casing is of insulating material, but the present invention is applicable to metal casings by merely insulating conductor 24 from the casing in known manner. The battery is well protected against short-circuit, and inadvertent lighting of the lamp will not oc-

cur when the hand lamp is laid on a metal surface or placed among metal tools. The inner lamp terminal is protected from destructive pressure and the hand lamp as a whole has many advantages that will be apparent to those skilled in the art.

Changes in structural details and in the arrangement of the several parts may be made without departing from the spirit of my invention as defined by the appended 75 claims.

I claim:

1. In a tubular hand lamp, the combination of a casing, a battery and a lamp therein arranged co-axially thereof, a fixed abutment for the front end of said battery, a reflector for said lamp, and screw threaded means adapted to be turned by hand for positively moving said lamp at will with respect to said abutment and reflector to 85 change the spread of the beam of light delivered by said hand lamp.

2. In a tubular hand lamp, the combination of a casing, a battery and a lamp therein arranged co-axially thereof, a fixed abutment for the front end of said battery, a reflector for said lamp, and means threaded to 90 said casing for moving said lamp with respect to said abutment to change the spread of the beam of light delivered by said hand lamp.

3. In a hand lamp, the combination of a casing, a battery and a lamp therein, a fixed abutment for the front end of said battery, a reflector for said lamp, an adjusting sleeve 100 encircling the front end of said casing, and means actuated by said sleeve for moving said lamp with respect to said reflector to change the spread of the beam of light delivered by said hand lamp.

4. In a hand lamp, the combination of a casing, a battery and a reflector therein, a fixed abutment for said battery, a lamp support mounted to slide in said abutment, a lamp carried by said support, and means on 110 said casing for sliding said support in said abutment to move said lamp with respect to said reflector.

5. In a hand lamp, the combination of a casing, a battery and a reflector therein, a 115 fixed abutment for said battery, said abutment having a tubular extension, a lamp support mounted to slide in said tubular extension, a lamp carried by said support, an adjusting sleeve encircling said casing, and means actuated by said sleeve for moving said lamp support in said abutment to change the spread of the beam of light delivered by said hand lamp.

6. In a hand lamp, the combination of a 125 casing, a battery and a reflector therein, an abutment for said battery, a lamp support mounted to slide in said abutment, a lamp carried by said support, an adjusting sleeve encircling the front end of said casing, and 130

a cross-bar actuated by said sleeve and operatively engaging said lamp support to move the same axially of the hand lamp when said sleeve is adjusted.

- 5 7. In a hand lamp, the combination of a casing, a battery therein, a battery abutment secured to said casing, a spring holding said battery against said abutment, a metal head attached to the front end of said 10 casing, a lens and a reflector secured to the front end of said head, a lamp support mounted to slide in said abutment, a lamp carried by said support, a threaded adjusting sleeve, and a cross-bar actuated by said 15 adjusting sleeve and operative to move said support to change the character of the beam of light delivered by said hand lamp.
8. In a hand lamp, the combination of a casing, a battery therein, a battery abutment secured to said casing, a spring holding said battery against said abutment, a metal head attached to the front end of said 20 casing, a lens and a reflector secured to the front end of said head, a lamp support of insulating material mounted to slide in said abutment, a lamp carried by said support, an adjusting sleeve threaded to said metal head, means connecting said adjusting sleeve with said lamp support to move said 25 lamp support and thereby change the character of the beam of light delivered by said hand lamp, and means for maintaining electrical connection with said lamp during adjustment of said sleeve.
- 30 9. In a hand lamp, the combination of a casing, a battery therein, a fixed battery abutment secured to said casing and having a tubular extension a closure for the rear end of said casing, a spring carried by said 35 closure and holding said battery against said abutment, a metal head attached to the front end of said casing, a lens and a reflector secured to the front end of said head, a lamp support of insulating material 40 mounted to slide in the tubular extension of said abutment, a lamp threaded into said support, an adjusting sleeve threaded to said metal head, a cross-bar actuated by said 45 adjusting sleeve and operative to move said support axially of said hand lamp and thereby change the character of the beam of light delivered by said hand lamp, and means for maintaining electrical connection with said lamp during adjustment of said 50 sleeve.
- 55 10. In a hand lamp, the combination of a cas-
- ing, a battery therein, a fixed battery abutment secured to said casing and having a tubular extension, a closure for the rear end of said casing, a spring carried by said closure and holding said battery against 60 said abutment, a flaring metal head rigidly attached to the front end of said casing, a lens holder threaded to said head, a reflector clamped between said lens holder and the end of said 65 head, a cylindrical lamp support of insulating material mounted to slide in the tubular extension of said abutment, a lamp carried by said support, an adjusting sleeve encircling the front end of said casing and 70 threaded to said flaring metal head, a cross-bar actuated by said adjusting sleeve, said bar fitting in a slot in said lamp support and being operative to move said support axially of said hand lamp and thereby 75 change the character of the beam of light delivered by said hand lamp, and means for maintaining electrical connection with said lamp during said adjustments.
11. In a hand lamp, the combination of a 80 casing, a battery therein, a fixed battery abutment secured to said casing and having a tubular extension, a closure for the rear end of said casing, a spring carried by said closure and holding said battery against 85 said abutment, a flaring metal head rigidly attached to the front end of said casing, a lens holder threaded to said head, a reflector clamped between said lens holder and the end of said head, a cylindrical lamp support of insulating material mounted to slide in the tubular extension of said abutment, a lamp threaded into said support, a collar encircling said support and having a yielding finger in contact with the outer lamp 90 terminal, a lug on said collar, a conductor yieldingly bearing on said lug, switch mechanism between said conductor and said closure spring, an adjusting sleeve threaded to said flaring metal head, a cross-bar actuated by said 95 adjusting sleeve, said bar fitting in a slot in said lamp support and being operative to move said support axially of said hand lamp and thereby change the character of the beam of light delivered by said hand 100 lamp, and a coiled spring positioned centrally in said insulating lamp support and maintaining electrical connection between said lamp and said battery.

In testimony whereof I affix my signature.

ARTHUR L. STAPLES.
